METHOD OF MAKING GROMMETS

Archibald M. Naysmith, James F. Drew, and Josef Budzinski, Kenosha, Wis., assignors to Mac-whyte Company, Kenosha, Wis., a corporation of Illinois

Application May 19, 1939, Serial No. 274,598

7 Claims. (Cl. 57—158)

This invention relates to a grommet and to the method of making it. It has for one object to provide a grommet made of a single piece of rope or cable which when the process of manufacture has been completed is spliced or otherwise made endless. Another object is to provide a method of making such a grommet.

Other objects will appear from time to time throughout the specification and the claims.

10 The invention is illustrated more or less diagrammatically in the accompanying drawings, wherein:

Figure 1 illustrates the core when bent;

15 Figure 2 illustrates the core when soldered or welded or joined by any other means;

Figure 3 illustrates the method of making, in which one wire or rope strand has been positioned about the core;

20 Figure 4 illustrates the grommet after all but the center wire or rope has been put in position;

Figure 5 is a transverse section taken on an enlarged scale at line 5—5 of Figure 4, showing the grommet before the core is removed;

25 Figure 6 is an elevation showing one step in the removal of the core;

Figure 7 illustrates a section of a completed grommet after the core has been removed, showing particularly the point at which the strands are diverted to the center to replace the original or "false" core;

30 Figure 8 illustrates one step in the process of splicing the strand, rope or cable which is put in place after the original working core has been removed;

35 Figures 9 and 10 illustrate particularly steps in splicing the rope ends in the center, or permanent core, of a "cable laid" grommet.

Like parts are designated by like characters throughout the specification and the drawings.

40 1 is a core. Ordinarily, it will be made in the form of a rod or a wire. It is preferably welded, or otherwise joined, as at 2 to form a complete, endless ring.

45 As shown in Figure 3, one strand of a wire rope 4 has been wound about the core 1. For convenience, the rope is carried on a spool 5. The process which is begun, as shown in Figure 3, by wrapping or winding or "laying" the rope about the core is continued until the grommet 50 is completed except for the removal of the original working core 1 and the substitution of a final or permanent strand of rope or wire 4 takes its place and completes the grommet.

55 When the process is complete to the point shown in Figures 4 and 5, the grommet is held

in a vise 6, or otherwise, and may be to some degree unwound for a portion of its length so that the resistance to removal of the core 1 is reduced. As shown, the core has been partly pried out by means of a spike 7. The wire or 5 rope or cable 4 has been laid in place except for the final strand which takes the place of the core when the latter is removed.

After the core is removed, a final strand of the member 4 is wound or laid into the grommet and the grommet may be partially opened or unwound successively about its circumference to permit the final strand to fall into place. When the grommet is completed, such a strand occupies the place of the core 1, as shown in 15 Figure 5. This portion of the grommet is indicated in Figures 7 and 8 primarily by the numeral 8. It is, of course, preferably continuous with the member 4 which forms the total grommet. 20

When the grommet has been completed, two ends of the permanent core remain to be spliced. They are, as shown in Figure 8, indicated by the characters X and Y. The splice has been partially completed, as shown in that figure, and comprises the portion Z. In making the final splice, all of the wires involved may be woven into the splice or parts may be removed by being cut off. For example, the ends 9, 10, 11 and 12 may be either worked into the splice or they 30 may be cut off and discarded.

In general, the core may be removed by a variety of methods and the invention is not limited to the exact steps described but may be generally understood to comprise the steps of 35 forming a grommet by laying successive strands about a core, thereafter removing the core and applying a further strand to take the place of the core and finally joining the ends of the rope by splicing or otherwise to finish the grommet. 40 The grommet is, thus, made of a single, continuous piece of material which has two ends only, which ends are secured against unraveling and displacement in any manner desired.

While the method of finishing the grommet 45 by splicing or otherwise securing the ends of the grommet-forming member may be accomplished in many different ways, two are described below:

The grommet of this invention may be either a "rope-laid" grommet or a "cable-laid" grommet. A "rope-laid" grommet is one formed from a single strand and the direction of the grommet "lay" is usually opposite to the direction of the "lay" of the strand. A "cable-laid" grommet is one formed from a rope (the rope being 55

itself formed from a plurality of strands laid to form a rope). The direction of the grommet "lay" is usually opposite to the direction of the rope "lay."

5 Whichever form of grommet is to be made, either rope "lay" or cable "lay," the diameter of the false or temporary core is preferably somewhat larger than the strand or rope from which the grommet is to be made. In forming the 10 grommet, the strand or rope from which it is to be made is selected and cut to the length required for the finished circumference of the grommet. The false core is generally cut somewhat shorter than the required finished circumference 15 of the grommet because the latter generally lengthens when the false center is removed. This is, in part, due to the fact that the false center is, as above pointed out, normally somewhat larger in diameter than the strand or rope 20 used in making the grommet.

While the length of strand or rope which is required to make a grommet of any specified, finished circumference may be determined in many ways, one simple method of determining 25 this length is by multiplying the circumferential length by 1.05, then by 6, and by adding to the result the circumferential length; i. e., 6 (circ. $\times$ 1.05) plus circ. The factor 1.05 will in that case be a function of the grommet "lay" and the finished diameter of the grommet and, as indicated, 30 is used to allow for take-up or shortening due to the helical path of the six outer strands or ropes as they lie in the grommet. This method of calculation is given merely as embodying one suitable 35 and convenient method. The invention is not limited to it.

Whichever type of grommet is made, either "rope-laid" or "cable-laid," the final finish of the grommet requires, as above mentioned, the 40 removal of the false core and the securing of the ends, either of the strand or of the rope.

After laying of the grommet is completed, the ends of the strand or rope are held back and the spike 1 is forced in as shown in Figure 6. The 45 false center is cut with a hacksaw, or otherwise. In a "rope-laid" grommet, the ends X and Y of the strand 4 are tucked to replace the core 1 by forcing one end of the core 1 out of the center of the grommet for a few inches with the spike 50 1 and then forcing a spike under two strands surrounding the core 1; the end X of the strand 4 is, thus, brought under the point of the spike and forced into the center of the grommet. By 55 rotating the spike about the grommet, the core 1 is progressively forced out and the end of the strand 4 is progressively forced in to assume the position formerly occupied by the false core 1 and to become a permanent core. Now the grommet is moved in the vise so that the end Y of the 60 strand 4 is held to prevent it from "un-laying" or becoming loosened. The other end of the core 1 is forced out of the center of the grommet and the end Y is progressively forced in to replace the false core as the latter is progressively removed. Finally, the false core is completely 65 removed and a strand 4 occupies the position formerly occupied by the false core. Thus, working from both ends, the false core has been removed and the new core, comprising a section of the 70 strand Y, has been forced into the center. The ends X and Y are forced into the center and the completed grommet assumes the condition shown in Figure 7.

In the case of a "cable-laid" grommet, the procedure for the removal of the false core 1 and the

replacement on insertion of the ends X and Y of the rope 4 is similar to that just described for a "rope-laid" grommet but with the exception that the tuck is locked by passing one rope end through the other rope end. Three strands or 5 more of rope X are lifted by means of a spike, and rope Y is pushed through the opening thus formed, thus locking the tuck. Then, ends X and Y are forced into the center of the grommet to form the permanent core. In Figures 9 and 10, 10 there is illustrated the splicing of the rope ends of a "cable-laid" grommet; that is to say, the splicing of the rope ends X and Y. As shown in Figure 9, the rest of the "cable-laid" grommet has been omitted. As shown in Figure 10, it is 15 dotted in. When the "cable-laid" grommet of Figures 9 and 10 is substantially completed, that portion of the grommet where the rope ends emerge is placed under light tension and is partially untwisted or unlaid, thus fully exposing the 20 ends to be spliced. The procedure from there on is similar to that used in making a long or endless splice, the alternate strands of each rope end X and Y replacing the strands in the opposite rope until the splice is completed and the 25 two rope ends X and Y are properly spliced together. When that is completed, then that portion of the grommet which has been untwisted or unlaid is allowed to twist again into shape. The 30 operation of joining the ends X and Y may be shortened by carrying each strand to be tucked under one strand and tucking it under two strands. Thus, the invention is not limited to any particular means of splicing or securing together the ends of the rope after the grommet 35 has been laid, and the method illustrated in Figures 9 and 10 is merely one suitable method.

As above pointed out, the invention is not limited to the particular type of final securing of the member from which the grommet is made 40 whether the latter be merely a strand or a rope.

Although there is shown an operative form of the device, it will be understood that many changes in the form, shape and arrangement of parts might be made without departing from the 45 spirit of this invention; and it is wished that the showing be taken as in a sense diagrammatic.

We claim:

1. The method of making an endless grommet which comprises the following steps: making a 50 ring-like, endless core of suitable diameter and thickness for the size of grommet desired, winding about the core successive, continuous strands of rope, thereafter breaking and removing the core, and replacing the core by an additional strand of rope.

2. The method of making an endless grommet which comprises the following steps: making a 55 ring-like, endless unitary core of suitable diameter and thickness for the size of grommet desired, winding about the core successive, continuous strands of rope, thereafter breaking and removing the core, replacing the core by an additional strand of rope, securing together the ends 60 of the rope.

3. The method of making an endless, flexible grommet which comprises the following steps: making a ring-like, endless unitary core of suitable diameter and thickness for the size of 65 grommet desired, said diameter being uniform throughout the length of said core, winding about the said core successive, continuous strands of rope, thereafter breaking and removing the core, replacing the core by an additional strand 70 75

- of rope, securing together, by splicing, the ends of the rope.
4. The method of forming a wire rope grommet, which includes the following steps: forming a ring of a single section of wire of suitable diameter and thickness to provide a grommet of the desired diameter, winding about said core and about the diameter of said core a succession of continuous unbroken wire rope strands 5 until said core is completely surrounded, thereafter progressively removing said core from the grommet and progressively adding a final, continuous strand of rope, forcing said strand progressively into the space vacated by said core.
- 10 5. The method of forming a wire rope grommet, which includes the following steps: forming a core ring of suitable diameter and thickness to provide a grommet of the desired size, winding about said core ring and about the diameter of said core a succession of continuous wire rope strands until said core is completely surrounded, thereafter progressively removing said core from the grommet and progressively adding a final, continuous strand of rope, forcing said strand progressively into the space vacated by said core and finally securing together the two ends of said wire rope.
- 15 6. The method of forming a wire rope grommet, which includes the following steps: forming a core ring of suitable diameter and thick-

ness to provide a grommet of the desired size, making said ring endless, winding about said core and about the diameter of said core a succession of continuous, unbroken wire rope strands until said core is completely surrounded, thereafter severing said core and progressively removing said core from the grommet and progressively adding a final, continuous strand of rope, forcing said strand progressively into the space vacated by said core.

10 7. The method of forming a wire rope grommet, which includes the following steps: forming a core ring of suitable diameter and thickness to provide a grommet of the desired size, making said ring endless, winding about said core 15 and about the diameter of said core a succession of continuous wire rope strands until said core is completely surrounded, thereafter severing said core and progressively removing said core from the grommet and progressively as the core is removed adding a final, continuous strand of rope, forcing said strand progressively into the space vacated by said core as the latter is removed, and finally securing together, by splicing within the grommet, the two ends of said wire rope, 20 25 after the last strand has been forced into the place from which the core was removed.
